UNITED STATES PATENT OFFICE.

MAX KLAAS, OF MONTCLAIR, NEW JERSEY.

DESIGN FOR A MANICURE INSTRUMENT.

48,495.

Specification for Design.

Patented Feb. 1, 1916.

Application filed March 29, 1913. Serial No. 757,714. Term of patent 14 years.

To all whom it may concern:

Be it known that I, MAX KLAAS, a citizen of the United States, residing at Montclair, in the county of Essex and State of New Jersey, have invented a new, original, and ornamental Design for Manicure Instruments, of which the following is a specification, reference being had to the accompanying drawing, forming part thereof.

In the drawing, Figures 1, 2 and 3 are

respectively top, side and bottom views of a manicure instrument, showing my new design.

I claim:

The ornamental design for a manicure instrument, as shown.

MAX KLAAS.
